FIG. 2.

FIG. 3.

FIG. 4.

INVENTOR:
John A. Erne
BY David E. Carlsen
ATTORNEY.

UNITED STATES PATENT OFFICE

JOHN A. ERNE, OF SPOKANE, WASHINGTON

PLIERS

Application filed September 23, 1929. Serial No. 394,522.

My invention relates to improvements in pliers and like implements and the main object is to provide holding means formed integral with the jaws or pivoted on each jaw, 5 said means particularly adaptable for engaging objects such as bolt heads to prevent rotation of the bolt when the same is being removed from or put in its place.

The preferred construction, with a modification is fully illustrated in the accompanying drawings and hereinafter fully described, reference being had to the drawings in which,

Fig. 1 is a face view of approximately the 15 front half of a pair of pliers with my improved holding means formed integral with its jaw members.

Fig. 2 is a full side elevation or edge view 20 of the pliers in Fig. 1, shown in operative position engaging the head of a bolt.

Fig. 3 is an enlarged modified view of the front part of a pair of pliers in same position as in Fig. 2.

Fig. 4 is a face view of Fig. 3 looking upwardly toward the jaw members in said latter figure.

Referring to the drawings by reference numerals, 5-6 designate the usual counterpart members of a pair of pliers, crossed and pivotally connected at 7, the jaw parts of said members being designated respectively as 5J and 6J. Said jaws may be of considerably variable forms but a common type being illustrated having inwardly of their clamping faces 5F-6F an arched row of serrations or teeth 8 for grasping various objects, and inwardly of said toothed parts wire cutting means 9 of well known type.

10 in Fig. 2 represents any part or parts of a machine structure through which extends a round head machine bolt 11, the head of which is designated 11H and the nut 11N.

An object of my improved pliers is to hold 45 or grasp the head of such a bolt or to grasp the perimeter of a flat-head type of bolt while the nut 11N is being removed as with a wrench 12 indicated in dotted lines only. In the mechanical field it is well known that nuts as 11N are exposed to the elements and 50 corrosion will cause the nut to stick when it

is desired to remove it and makes the said removal very difficult and nearly impossible because the bolt will rotate with the nut.

My improved pliers are provided with a circular row of fingers 14, half of them on 55 each jaw member 5J or 6J and all extending outwardly sidewise from the jaws and tapering, all of them terminating in inwardly radially directed ends, the said termini being in a plane at an acute angle to the plane of 60 the pliers. For example, when the pliers are held in an inclined plane, jaws forward and down, the extremities of the fingers 14 are in a horizontal plane and spaced apart in such a manner that when a hand clamps the 65 jaws 6J and 5J toward each other by pressing the handles 5-6 toward each other, the said fingers will engage the bolt head 11H on diametrically opposite parts, in 4 places when there are two fingers on each jaw. 70 Thus the bolt head is securely held while a monkey-wrench is employed to remove the nut 11N. Where countersunk bolt heads, in wood, are to be engaged, the fingers 14 may of course be pressed into the surface around 75 said head and then closed toward each other to engage the perimeter of such head. Obviously the finger members 14 are automatically self-adjusting to the perimetral rim of the head 11H when the plier handles are 80 pressed toward each other.

The common plane of the fingers 14 angular with relation to the plane of the pliers, is an important feature, the operator being enabled to exert downward pressure while 85 holding the pliers angularly as shown in Fig. 2.

The number of fingers 14 is optional, it being in some cases likely that three or more may be used on each plier jaw but two on 90 each jaw have been found very efficient and being directed inwardly and diametrically toward the fingers of the opposite jaw, will readily engage and hold various sizes of bolt heads or the like.

The construction or mounting of the finger members shown in Figs. 3 and 4 is simply a modification of the principle of my improved pliers in which said fingers are not integral with the jaws, but formed in pairs 14J, one 100

pair to each jaw and integral with a head 14H, each said head having further a pin 14P arranged to be journaled in an angular bore 17 in the jaw. In said finger members 5 the pins 14P are located outwardly of the finger parts. Thus when the plier jaws are spread to engage a bolt head, said members 14H are clamped against opposite sides thereof on a line diametrical of the bolt head 11H 10 when the plier handles are squeezed and the fingers 14 automatically engage the bolt head, the pins 14P being located one in each jaw in a line drawn transversely through the jaws, (see line 18 in Fig. 4).

15 My improved pliers have now been fully described.

I claim:

1. In a tool of the class described comprising in part a pair of gripping jaws with parallel outside faces, pivot means rearward of said jaws and handle means extending from said pivot, an auxiliary jaw member rotatably mounted on each jaw, fingers on each said jaw extending radially inwardly and 25 formed integral with each auxiliary jaw.

2. In a tool of the class described comprising in part a pair of gripping jaws with parallel outside faces, pivot means rearward of said jaws and handle means extending from 30 said pivot, an auxiliary jaw member rotatably mounted on each jaw, fingers on each said jaw extending radially inwardly and formed integral with each auxiliary jaw, said fingers of each latter jaw having their finger 35 extremities terminating in a common plane and in chisel-like edges in a plane at an acute angle with relation to the common plane of the pliers.

3. The structure specified in claim 1 in 40 which the mounting means for said auxiliary jaws comprises for each an integral pin rotatably retained in the jaw, outwardly of said finger parts and transversely of the pliers.

45 In testimony whereof I affix my signature.

JOHN A. ERNE.
